UNITED STATES PATENT OFFICE

146,022

DESIGN FOR AN ELECTRIC STEAM RADIATOR

Herbert J. Freyman, New York, N. Y.

Application June 18, 1945, Serial No. 120,181

Term of patent 14 years

(Cl. D81—21)

To all whom it may concern:

Be it known that I, Herbert J. Freyman, a citizen of the United States of America and residing at New York city, in the county and State of New York, have invented a new, original, and ornamental Design for an Electric Steam Radiator, of which the following is a specification, reference being had to the accompanying drawing, forming a part thereof.

The figure is a perspective view of an electric steam radiator, showing my new design.

The side of the radiator not shown in the drawing is substantially like the side shown, with the exception of the omission of the thermostat.

I claim:

The ornamental design for an electric steam radiator, substantially as shown and described.

HERBERT J. FREYMAN.
